UNITED STATES PATENT OFFICE.

JOHN M. WILSON, OF SAN DIEGO, CALIFORNIA.

TOBACCO PIPE.

Application filed October 10, 1923. Serial No. 667,714.

To all whom it may concern:

Be it known that I, JOHN M. WILSON, a citizen of the United States, and resident of San Diego, and county of San Diego, State of California, have invented certain new and useful Improvements in Tobacco Pipes, of which the following is a specification.

It is well known that when tobacco is smoked in a pipe it always leaves a residue that not only is disagreeable and harmful to the smoker, but that is a constant source of annoyance and trouble due to its rapid collection in such quantities within the bores of the stems of pipes of most commercial types as to choke the stems and thereby necessitate frequent cleaning of the same. Accordingly it has been my purpose in producing my present improvements to provide a pipe in which the smoke is filtered and the residue therefrom collected during passage of the smoke through the stem of the pipe whereby substantially all disagreeable, harmful and annoying effects from the residue are eliminated.

With the foregoing and other purposes in view my invention consists in the novel features of construction, combination and arrangement of parts as will be hereinafter more fully described, illustrated in the accompanying drawings and defined in the appended claims.

In the drawings, wherein like characters of reference denote corresponding parts in the different views

Figure 1 is a longitudinal section through a pipe embodying the novel and essential features of my invention;

Figure 2, a side elevation;

Figure 3, top plan of the bowl portion of the pipe;

Figure 4, a detail perspective of the removable cage or holder for the filtering and residue collecting material; and

Figure 5, a section on the line 5—5 of Figure 1.

Referring now to the drawings in detail, 10 designates the bowl of my improved pipe, 11 its stem and 12 its detachable mouth-piece. Bowl 10 is provided with the usual tobacco chamber 13 and stem 11 is provided with a bore 14 of large diameter that extends across the bottom of said tobacco chamber and communicates therewith through the latter's somewhat restricted bottom portion 15, which portion is sub-

stantially of the same diameter as bore 14 as shown.

Rotatably and removably fitted within the bore 14 of stem 11 is a cage 16 that preferably is pressed or stamped from a single piece of material such as sheet metal and that consists of a tubular body, segments of the inner end portion of which are cut away leaving a plurality of longitudinally extending bars 17 which preferably are three in number and evenly spaced circumferentially of the body as clearly shown in Figures 4 and 5 of the drawings. These bars connect the cap-like inner end 18 of the body with its outer unperforated end portion 19, and this latter portion is extended terminally outward and then inward towards the other end of the body with the result that the cage is provided at its outer end with a thimble 20 that is disposed in outwardly spaced, concentric relation with respect to the outer end portion of the cylindrical body as is apparent. Thimble 20 preferably is knurled or milled as indicated at 21 to provide a convenient finger grip for rotating the cage, it being observed from the showing in Figure 1 that the cylindrical body of the cage is disposed entirely within the bore 14 of stem 11, while the thimble 20 snugly engages over the outer end of the stem and not only provides means for rotating the cage, but serves as a seal to exclude air from bore 14, in which connection I desire to point out that if necessary a suitable gasket may be placed between the outer end of the stem 11 and the portion of the cage that overlies said outer end whereby air may positively be excluded from said bore.

Mouthpiece 12 is provided with a reduced inner end 22 that fits within the outer end portion of the cylindrical body of the cage, the smoke duct in said mouthpiece being in communication with the tobacco chamber 10 in the bowl 10 through the cage and bore 14 as is manifest.

In the use of my improved pipe a suitable smoke filtering and residue collecting substance or material 23 such as commercial steel wool is placed within the cylindrical body of the cage between the inner end of the mouth piece 12 and the cap 18 either prior to or after the cage is engaged, as shown in Figure 1, with the bowl and stem of the pipe, and by means of the thimble 20, the cage is rotated until one of the open

2
spaces between adjacent bars 17 underlies the restricted bottom portion 15 of the tobacco chamber 13, in which position the material 23 constitutes the bed of the tobacco chamber. Thus it is apparent that all smoke passing from chamber 13 to the mouthpiece 12 must pass through and be filtered by the material 23 which material also acts to collect all residue such as ash, 10 carbon, oil and nicotine as is further apparent.

Since the cylindrical body of the cage 16 is provided with plural bars 17 and an equal number of cut out spaces between said 15 bars, rotation of the cage through a predetermined angle, in this instance 120° , will dispose a new and clean part of the material 23 beneath the tobacco chamber 13 whenever the material between a given pair of 20 bars becomes saturated with residue. When the cage has been rotated to successively dispose all of the spaces between the bars 17 beneath the chamber 13, the cage may be withdrawn from the stem, the material 23 25 removed therefrom and clean material substituted.

Since the body portion of the cage fits snugly within the bore 14, it is manifest that rotation of the cage causes the bars 17 30 to act throughout their length as scrapers which assures that all deposits will be removed from the wall of said bore and the latter as a consequence be maintained constantly clean.

35 Due to the large bore in the stem 11 and the equally large opening in the bottom of the tobacco chamber through which the smoke passes into said bore all annoyances such as are commonly due to choking of 40 tobacco pipes are eliminated in my improved pipe. Furthermore, my improved pipe is cheap and easy to produce, strong, durable, readily and easily cleaned and thoroughly efficient for its purpose.

45 Various changes and desirable additions

may be made in and to my improved pipe within the spirit and scope of my invention as defined in the appended claims.

I claim:—

1. A tobacco pipe including a bowl provided with a tobacco chamber, a stem provided with a bore in communication with said tobacco chamber, and a cage for containing filtering and residue collecting material including a body portion disposed within said bore and provided with means for scraping the wall of said bore when the cage is rotated, and means disposed exteriorly of the stem for rotating said cage. 50

2. A tobacco pipe including a bowl provided with a tobacco chamber, a stem provided with a bore extending across the bottom of and communicating with said tobacco chamber, a cage including a tubular body portion disposed within said bore and a thimble portion fitting over said stem, said tubular body portion being segmentally cut away to provide circumferentially spaced bars, filtering and residue collecting material arranged within said tubular body 65 portion, and a mouth piece fitted within the outer end of said tubular body portion. 70

3. A tobacco pipe including a bowl provided with a tobacco chamber, a stem provided with a relatively large bore extending entirely across the bottom of and intersecting said tobacco chamber, a mouthpiece extending from said stem, filtering and residue collecting material arranged within said bore at the bottom of the tobacco chamber 80 so as to constitute a bed for tobacco contained within said chamber, and means operable independently of said mouthpiece while the latter is engaged with the stem to rotate the filtering and residue collecting material within said bore, for the purpose set forth. 85

In testimony whereof I hereunto affix my signature.

JOHN M. WILSON.
